CLAIM

The ornamental design for a sound emitting bobber, as shown and described.

DESCRIPTION

FIG. 1 is a top, front, right side perspective view of a sound emitting bobber, showing our new design;

FIG. 2 is a front elevational view, the rear being a mirror image thereof;

FIG. 3 is a left side elevational view, the right side being a mirror thereof;

FIG. 4 is a top plan view; and

FIG. 5 is a bottom plan view.
